(57) **CLAIM**

The ornamental design for a lamp, as shown and described.

DESCRIPTION

FIG. 1 is a perspective view of a lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 1.

The lamp is shown with a symbolic break in its length and the appearance of any portion of the lamp between the break lines form no part of the claimed design. The broken lines in FIGS. 1, 9 and 10 shown encircling the partial enlarged detail views are for annotative purposes only and form no part of the claimed design.

1 Claim, 10 Drawing Sheets
